UNITED STATES PATENT OFFICE.

WILLIAM B. MURRAY, OF DANVILLE, ILLINOIS, ASSIGNOR TO THE MILLER TRAIN CONTROL CORPORATION, OF STAUNTON, VIRGINIA, A CORPORATION OF VIRGINIA.

TRAIN-CONTROL MECHANISM.

Application filed May 16, 1924. Serial No. 713,786.

To all whom it may concern:

Be it known that I, WILLIAM B. MURRAY, a citizen of the United States, residing at Danville, in the county of Vermilion and State of Illinois, have invented certain new and useful Improvements in Train-Control Mechanism, of which the following is a specification.

This invention relates to train control mechanism, and is an improvement over the construction disclosed and claimed in my prior Patent No. 1,431,025, granted October 3, 1922.

In the train control apparatus described in the said prior patent, there is provided a pressure actuated device or pressure motor connected to the engineer's air brake valve lever, which device is normally retained in an inoperative position by means of a balanced pressure. A magnet valve is arranged in the outlet from the pressure cylinder, which valve is normally in open position but is adapted to be closed by the magnet when the train passes an energized ramp and current is furnished to the magnet. The apparatus further comprises a shoe carried by the train and adapted to contact with inclined ramps arranged on the roadway, the shoe being provided with a valve arranged in the outlet conduit which is opened upon each actuation of the shoe, thus opening the conduit to the atmosphere when the shoe valve and magnet valve are both opened to apply the brakes and stop the train.

In the present invention, I provide an apparatus of the same general character having a magnet valve controlled by the energization and de-energization of the ramp in the same manner as the magnet valve of my prior patent and between the magnet valve and the pressure motor, there is interposed a second valve arranged in a local train circuit, which circuit includes a movable contact carried by the shoe and adapted to be broken upon each actuation of the shoe.

This eliminates the necessity of the conduit extending from the magnet valve casing to the shoe and permits the conduit to be opened to the atmosphere just beyond the second valve casing which is arranged adjacent the pressure motor cylinder.

In the accompanying drawings, I have shown one embodiment of the invention. In this showing:

Figure 1 is a front elevation of a portion of a locomotive showing the invention applied,

Figure 2 is a similar view of the shoe,

Figure 3 is a similar view of the pressure motor and valves showing the arrangement of the same in connection with the engineer's air brake valve,

Figure 4 is a horizontal sectional view on line 4—4 of Figure 2, and,

Figure 5 is a diagrammatic view of a portion of a track showing the arrangement of track circuits.

Referring to the drawings, the reference numeral 1 designates the casing of an engineer's air brake valve of usual construction which is mounted on the vehicle at any suitable point, preferably in the engineer's cab. A shaft (not shown), extends through this casing and is provided with a lever 2 to permit revolution of the shaft to open or close the valve and apply the brakes. This lever is provided with a handle portion 3. The control apparatus forming the subject matter of the present invention consists of a cylinder 4 which is closed at its lower end and is provided with a port 5 for the introduction of air or other fluid under pressure. As shown, this port communicates with the top of the cylinder through a transverse port 6. These ports are adapted to be connected to a source of fluid under pressure, such as the air reservoir of the vehicle, by means of a pipe 7. The upper end of the cylinder is closed by a head 8, which is provided with a central boss 9. A piston 10 is arranged within the cylinder, and this piston is provided with a piston rod 11, extending through the boss 9. The piston rod is adapted to be surrounded by suitable packing 12, held in position by a packing gland 13 and a packing nut 14, which engages threads formed on the exterior of the boss 9. The inner end of the boss is surrounded by a suitable strip of packing 15. A bracket 16 is supported on the top of the cylinder and this bracket is adapted to support a steel roller 17, mounted on a pin 18. A chain 19 preferably formed of steel, is connected to

the piston rod. The chain may be connected to the piston rod in any suitable manner but, as shown, the piston rod is provided with a longitudinal slot 20 at its upper end 5 and one end of the chain is arranged therein and adapted to be maintained in position by means of rivets or other suitable fastening elements. A drum 21 is secured to the shaft of the air brake valve and the other end of 10 the chain is adapted to be secured to this drum. The drum is provided with a flange 22 forming a guide or guard for the chain and is further provided with a depending lug or pin 23, adapted to engage one side 15 of the air brake lever. A bracket 24 is secured to the casing of the air brake valve and extends upwardly. This bracket and the bracket 16 are adapted to receive and support a cover plate 25, arranged over the 20 chain.

A valve casing 26 is arranged adjacent the pressure motor cylinder. This valve casing is provided with a main inlet passage 27, communicating with a port 28 extending 25 through the cylinder wall to the bottom of the cylinder and communicating through a port 29. The piston 10 is provided with a passage 30 whereby fluid passes from the top of the cylinder to the bottom to normally establish a balanced pressure in the cylinder. The valve casing is provided with a partition 31 having an opening therein communicating with a chamber 32 in the bottom of the valve casing. The opening is 35 provided with a valve seat 33 adapted to be engaged by a valve 34. The valve is provided with a depending stem 35, extending from the opening in the bottom 36 of the valve casing. It is likewise provided with 40 an upwardly extending stem 37, adapted to be received in a longitudinal opening in a boss 38 in the top of the valve casing. A solenoid 39 is arranged beneath the valve casing and the solenoid is provided with a core 40, adapted to be raised when the magnet is energized to engage the valve stem 35 and raise the valve to the closed position shown in Figure 3 of the drawings.

The secondary magnet valve, corresponding to the magnet valve shown in my prior patent, is mounted in a valve casing 41 arranged opposite the valve casing 26. As shown, the chamber 32 of the valve casing 26 is provided with an outlet passage 42, communicating with a passage 43 in the top of the secondary valve casing. It will be noted that the construction of the valve casings, valves and magnets is substantially the same and with a slight modification, either 55 valve casing may be employed as a primary or secondary valve. The secondary valve is provided with a chamber 44 at the bottom, communicating with the inlet passage 43 through an opening 45. This opening is 60 provided with a valve seat 46, adapted to be

engaged by a valve 47. The valve 47 is provided with a depending stem 48 passing through the bottom 49 of the valve casing and adapted to be engaged by a core 50, of a magnet 51. The upper end of the valve is 70 likewise provided with a stem 52, adapted to be received in an opening in a boss 53, formed on the top of the valve casing to form a guide for the valve. The secondary valve casing is provided with an outlet passage 54, communicating with a pipe 55 which is open to the atmosphere.

A shoe 56 consisting of a substantially cylindrical member is mounted on the vehicle and insulated therefrom. As shown, (see Figure 1) a bracket 57 is secured to any convenient part of the vehicle and the shoe is provided with flanges 58 by means of which it is secured to the face of the bracket. These flanges are provided with slots 59 for the reception of bolts 60 to permit vertical adjustment of the shoe. Suitable insulation 61 is arranged between the bracket and the shoe. The main portion of the shoe is provided with a central opening 62 which is reduced in cross section adjacent the bottom, forming a shoulder 63. A movable member 64, in the form of a plunger, is mounted in the lower portion of the cylinder and this movable member or plunger is provided with a flat plate 65 on its lower end, having flanges 66 formed on its opposite sides. A plate 67 of hard metal is arranged between these flanges and held in place by means of bolts 68. The plunger is provided with a 100 longitudinally extending opening 69 communicating with a reduced opening 70, extending to the bottom of the plunger and having a ball valve 71 arranged therein. This ball valve is normally retained in engagement with its seat by means of a spring 72, one end of which engages the flat plate 65 of the shoe proper. The interior of the cylinder is connected to the brake pipe by means of a pipe 73 and it will be apparent that if the lower portion of the shoe becomes disconnected, the tension on the spring 72 is released, opening the valve 71 and permitting the air or other fluid to exhaust from the brake pipe.

The shoe is adapted to engage a ramp 74 mounted on a suitable supporting member 75 and retained in position by suitable clamping members 76. When the shoe engages the ramp, the plunger 64 moves upwardly into the cylinder. The upper end of the plunger is provided with an enlarged portion 77 which is adapted to engage the shoulder 63 to limit its downward movement. Beyond the enlarged portion, the plunger is reduced 120 and threaded to receive a nut 78. This nut is provided with a central opening adapted to receive a stem or rod 79. The rod is provided with a collar 80 which engages the upper face of the nut 78 and a spring 81 is 130

arranged above this collar. A cylindrical member 82 is arranged on top of the cylinder 56 and insulated therefrom by means of a strip of insulation 83. The upper end of the 5 spring 81 engages the bottom 84 of the cylinder 82. The stem 79 extends through the bottom of the cylinder 82 and is provided with a collar 85 adjacent its upper end. A ring 86 of insulating material is arranged in the 10 cylinder wall and this insulating member 15 above this collar and retained in position by a nut 87. A strip of contacting material 88 is arranged around the insulating material. The insulating member 89 is arranged in the cylinder wall and this insulating member 20 carries a pair of contacts 90 arranged diametrically opposite each other and adapted to be engaged by a ring 88 of contacting material. These contacts are mounted on bolts 91 extending to the exterior of the cylinder 25 through an insulating material and serving as conductors. One of the bolts is adapted to receive a lead wire 92 connected to one terminal 93 of the primary valve magnet. The other terminal 94 of this magnet 30 is provided with a lead wire 95 connected to a binding post 96, arranged on the cylinder 82. The other bolt 91 is connected to a wire 97 which extends through a metal tube or pipe, as shown in Figure 2 of the drawings, 35 and is connected to one terminal of a source of current 98. As shown, a fuse 99 may be arranged in this lead wire. The other terminal of the source of current is provided with a lead wire 100, connected to the tube 101 in which the wire 97 is arranged. The 40 wire 102 is soldered to the tube, as at 103, and this wire is connected to a second binding post 104, arranged on the cylinder. The secondary valve magnet is provided with a terminal 105 connected to the shoe by a wire 106. The opposite terminal of the magnet is grounded, as indicated in Figure 5 of the drawings.

In Figure 5 of the drawings, the arrangement of ramps and the connections to form the necessary circuits are diagrammatically illustrated. As shown, the trackway is formed of a plurality of rails in the usual manner and the rail sections are separated by insulated joints 106' to form blocks A, B, and C. The signal is arranged at the entrance to each block, in the usual manner, adapted to be controlled by the track circuit and this signal is connected to a ramp arranged at braking distance in front of the entrance to the block to control the train. As shown, a track circuit is formed by means of lead wires 107 and 108, which are connected to the two rails of the track and to a source of current 109. A track relay 110 is also connected to the rails by lead wires 111 and 112. It will be apparent that a circuit normally exists in the block C when there is no train in the block or no disconnected rails, opened switches, or other breaks

in the track which would form a break in the circuit. The track relay 110 is adapted to control a signal circuit which includes a source of current 113. As shown, signal wires 114 and 115' extend along the track 70 and the source of current 113 is connected to the wire 114 by a lead wire 115. The wire 114 serves as a ramp control wire and is connected to ramp relay 116 by a branch wire 117. The ramp relay is provided with 75 a lead wire 118 which is connected to a movable contact 119 arranged adjacent the track relay and adapted to be influenced by the track relay. The contact 119 is adapted to be influenced by the track relay. The contact 119 is adapted to engage a lead wire 120 which is connected to a signal relay 121. A movable arm 122 is arranged adjacent this relay and this arm is connected to a pivoted signal 123 by means of suitable connections 80 85 124. When the arm 122 is attracted by an energized relay, the signal is maintained in the upper or clear position, as shown in full lines in Figure 5 of the drawings. When the relay is deenergized, a spring 125 is 90 95 connected to wire 115 by a wire 126 and the wire 115 is connected to the source of current by a wire 127.

The ramp 74 is arranged in advance of the entrance to block C, and this ramp is connected to a source of current 128 by means of a wire 129. A movable contact 130 is arranged in this connection and is adapted to be controlled by ramp relay 116. The opposite side of the source of current is connected to one of the rails by a wire 131.

In operation, air flows through the pipes 105 7 and ports 5 and 6 to the top of the cylinder 4. Sufficient air passes through the restricted port 30 in the piston 10 to equalize the pressure on the top of the cylinder and the conduit passages 27 and 28 are filled 110 with air. The apparatus is then in condition for operation, the valve 34 being normally retained in closed position by current from the source of current 98 and valve 47 being normally in the open position shown 115 in Figure 3 of the drawings. As the vehicle approaches a block, the movable portion of the shoe engages a ramp and is raised, moving the contact ring 88 upwardly 120 out of engagement with the contacts 90. This moves the valve 34 to an open position. If the ramp is deenergized, indicating a danger position, the magnet 51 remains deenergized and the valve 47 remains open, permitting air to flow from the bottom of the cylinder 4 to the atmosphere through the pipe 55. The piston is then forced downwardly by the pressure on its upper surface, pulling the chain 19 downwardly and operating the engineer's air 125 130

brake lever to apply the brakes. As soon as the shoe passes off the ramp, the circuit of the primary magnet valve 39 is re-established and the valve 34 closed, permitting the pressure to build up in the bottom of the cylinder and permitting the parts to assume normal position whereby the handle 3 of the air brake lever may be operated to close the air brake valve. This permits the engineer to release the brakes before the train comes to a dead stop, or if the tracks are slippery and the brakes have been applied suddenly, which frequently locks the wheels and causes skidding, it permits the engineer to release the brakes and then apply them more gradually.

When a train approaches a clear signal, the ramp 74 is energized and the shoe picks up current which is conveyed to the magnet 51 through the wire 106, energizing the magnet. The complete circuit is indicated in Figure 5 of the drawings. The current passes through the vehicle to the rail and thence to the source of current 128 through the wire 131. When the secondary magnet is energized, the core 51 is raised, raising the valve 47 into engagement with the valve seat 46. This cuts off communication between the lower end of the cylinder and the atmosphere and the raising of the movable portion of the shoe merely momentarily de-energizes the primary magnet 39 without applying the brakes. It will be seen that the valve 47 is normally in danger position and that a positive action, the energization of magnet 51, is necessary to permit a vehicle to pass a ramp. Further, any break in the apparatus will also cause an application of the brakes. The arrangement of the lead wires 92 and 95 on the cylinder 82 is such that current is prevented from passing to the magnet 39 if a short circuit should occur. In case of a short circuit, current will flow from wire 97 to the bolt 91 and will then return through the cylinder 82, wire 102 and pipe 101 to the source of current without passing through the magnet 39. This will immediately cause the valve 34 to assume an open position between ramps, and as the valve 47 is always in an open position between ramps, the lower end of the cylinder will be open to the atmosphere.

The signalling mechanism disclosed is of the usual type. The entrance to each block is provided with signalling mechanism as shown, and each block or track cut is provided with a track circuit. For simplicity, the track circuit of block C alone is shown in the drawings. With a clear block and no open switches, broken rails, or other disconnections, current normally flows from a source of current 109 through wire 107, one rail, wire 112, relay 110, wire 111, the other rail, and wire 108 to the source of current.

Thus, the track relay 110 is normally energized when a clear block exists. If a train enters the block, the current is short circuited through the wheels and axles of the train, deenergizing the relay. The contact 119 of the signalling circuit then moves out of engagement with the lead wire 120 and the signal drops to the danger position shown in dotted lines in Figure 5 of the drawings. When the relay 110 is energized current flows from the source of current 113 through wires 114, 115, and 117 to the ramp relay 116, then through wire 118, contact 119, wire 120, relay 121, wire 126, wire 115' and wire 127 to the source of current. It will thus be seen that when the signal is in clear position, the ramp relay is energized, attracting the contact 130 and closing the ramp circuit.

The pressure in the upper portion of the shoe cylinder 56, delivered through the pipe 73, forces the shoe proper downwardly insuring proper contact between the shoe and the ramp. As stated, the valve 71 is retained in position by the shoe proper and if the shoe proper becomes loosened or is broken off, the valve will be unseated and the air exhausted from the brake pipe.

If desired, a positive stop valve 132 may be connected to the bottom of the cylinder 4 by means of a pipe 133. The valve casing is provided with outlet openings 134, communicating with a passage 135, normally closed by a valve or plunger 136. A spring 137 engages a collar 138, formed on the valve support 139 and tends to force the valve to open position. The strength of the spring is such that the pressure normally existing in the bottom of the cylinder will overcome it and retain the valve in closed position. As soon as the pressure is released from the bottom of the cylinder, the spring opens this valve, thus opening the bottom of the cylinder to the atmosphere through the passages 134 and the valve remains in open position until the projecting portion 139 of the valve stem is raised, manually, or by other suitable control mechanism to close the valve.

It is to be understood that the form of my invention herewith shown and described is to be taken as a preferred example of the same, and that various changes in the shape, size, and arrangement of parts may be resorted to without departing from the spirit of the invention or the scope of the subjoined claims.

I claim:

1. In a train control system, a pressure operated device, an electrically operated valve to control the exhaust therefrom, means on the trackway for opening said valve at spaced intervals, a second electrically operated valve connected to the outlet of said first valve, and means controlled

by the track conditions to close said second valve during the period that the first valve is opened when the track is clear.

2. In a train control apparatus, a pressure operated device, a valve casing communicating therewith, a valve arranged in said casing, a magnet controlling said valve, a normally closed circuit to energize said magnet and retain said valve in a closed position, ramps on the trackway at spaced intervals, mechanical means engaging said ramps and adapted to break said circuit, a second valve communicating with the outlet of said first valve, a normally deenergized magnet controlling said valve, and electrically operated means controlled by the engagement of said mechanical means and said ramp for energizing said second magnet when the track is clear.

3. In a train control system, a track divided into blocks, a normally energized ramp arranged in advance of each block, said ramps being adapted to be deenergized by the presence of a train in the block, a pressure operated device mounted on the vehicle, a valve to control the exhaust from said device, a normally energized magnet adapted to maintain said valve in closed position, a local circuit on the vehicle connected to said magnet, a shoe adapted to contact with the ramp, a movable contact arranged in said local circuit and connected to said shoe to break said circuit and open said valve when the shoe and ramp are in engagement, a second electrically operated valve connected to the outlet of said first valve, and electrical connections between said second valve and said ramp to close said valve when the ramp is energized.

4. In a train control system, a track divided into blocks, a normally energized ramp arranged in advance of each block, said ramps being adapted to be deenergized by the presence of a train in the block, a

pressure operated device mounted on the vehicle, a valve to control the exhaust from said device, a normally energized magnet adapted to maintain said valve in closed position, a local circuit on the vehicle connected to said magnet, a mechanically operated device engaging said ramps and adapted to break said circuit to open said valve, a second valve connected to the outlet of the first valve, a normally deenergized magnet controlling said valve, and means controlled by the condition of the ramp for energizing said magnet and closing said valve.

5. A device constructed in accordance with claim 1 wherein said pressure operated device comprises a cylinder, means for supplying fluid to one end of said cylinder, and means to permit fluid to pass into the opposite end of the cylinder to establish a balanced pressure therein.

6. A device constructed in accordance with claim 2 wherein said pressure operated device comprises a cylinder, means for supplying fluid to one end of said cylinder, and means to permit fluid to pass into the opposite end of the cylinder to establish a balanced pressure therein.

7. A device constructed in accordance with claim 3 wherein said pressure operated device comprises a cylinder, means for supplying fluid to one end of said cylinder, and means to permit fluid to pass into the opposite end of the cylinder to establish a balanced pressure therein.

8. A device constructed in accordance with claim 4 wherein said pressure operated device comprises a cylinder, means for supplying fluid to one end of said cylinder, and means to permit fluid to pass into the opposite end of the cylinder to establish a balanced pressure therein.

In testimony whereof, I affix my signature.

WILLIAM B. MURRAY.
